CLEAN AIR WORK STATION

Anthony M. DiCiccianni, Norristown, Pa., assignor to
Laminar Flow, Inc., Conshohocken, Pa.

Filed Oct. 27, 1969, Ser. No. 19,738

Term of patent 14 years

Int. Cl. D24—01

U.S. Cl. D16—2

Fig. 1.

Fig. 3.

Fig. 2.

Fig. 5.

Fig. 4.

FIG. 1 is a perspective view of a clean air work station showing my new design;

FIG. 2 is an elevational view of the side not shown in FIG. 1;

FIG. 3 is a top plan view thereof drawn on a two-thirds scale of FIG. 2;

FIG. 4 is a bottom plan view thereof on the same scale as FIG. 3;

FIG. 5 is a rear elevational view thereof on the same scale as FIG. 3.

The side opposite that shown in FIG. 2 is a mirror image thereof.

The characteristic features of my design comprise the lower panel and the horizontal grille placed therein having elongated narrow louvers.

I claim:

The ornamental design for a clean air work station, substantially as shown and described.
